(57) **CLAIM**

The ornamental design for an illumination device, as shown and described.

DESCRIPTION

FIG. 1 is a first perspective view of an illumination device showing our new design;

FIG. 2 is a second perspective view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The difference in shading in the two claimed regions represents a contrast of appearance and no particular color. The broken line showing of various features of the illumination device depicts environmental subject matter only and forms no part of the claimed design.
